UNITED STATES PATENT OFFICE

2,478,437

COMBINED LEAD PENCIL AND ERASER

Hiram Earl Temple, Los Angeles, Calif.

Application September 17, 1945, Serial No. 616,731

3 Claims. (Cl. 120—38)

1

This invention relates to a combined lead pencil and eraser.

Heretofore various types of lead pencils have been provided in which a structure was used to permit the replacement of lead. Various structures have also been made in which a limited length of eraser can be replaced and fed out of the pencil as it requires replacement. Most of the structures of this general type are complicated and the supply of eraser included in them is quite limited. It is the principal object of the present invention, therefore, to provide a mechanical pencil in which refillable lead and an eraser may be carried and fed therefrom by the use of a simple, inexpensive structure.

The present invention contemplates the provision of a mechanical pencil structure having a tubular body member within which a tubular eraser is enclosed and partly through which eraser a lead pencil lead extends; the body structure carrying clamping means at one end to hold the lead in a set position and clamping means at the opposite end to hold the eraser in a set position.

The invention is illustrated by way of example in the accompanying drawings in which:

Figure 1 is a view in section and elevation showing a pencil embodying the present invention with parts broken away for the sake of clearness.

Fig. 2 is a view in transverse section through the pencil structure as shown on the line 2—2 of Fig. 1.

Fig. 3 is a view in side elevation showing the completely assembled pencil.

Fig. 4 is a view in end elevation showing the end of the pencil carrying the eraser.

Fig. 5 is a view in central longitudinal section through a modified form of the pencil structure as generally seen on line 5—5 of Fig. 3 and shows the central tube removed.

Fig. 6 is a view in end elevation showing the end of the pencil in which the lead is carried.

Referring more particularly to the drawing, 10 indicates an outer tubular body member. One end of this body member receives a tubular fitting 11. This fitting is pressed onto a cylindrical extension 12 thereon and abuts against an annular shoulder 13. Projecting beyond this shoulder is a threaded portion 14. The end of the threaded portion 14 is fitted with a pair of longitudinally extending yieldable jaws 15 which are substantially arcuate in section and combine to form a central bore 16 through which a pencil lead 17 extends. The outer faces of the jaws 15

2

are tapered as indicated at 18. Extending over these jaws is a tubular pencil tip 19, which has a centrally tapered bore 20 agreeing substantially with the tapered faces 18 of the jaws. The upper end of the member 19 is threaded, as indicated at 21, and receives a threaded extension 14 of the member 11. The fitting 11 is formed with a central bore 22 to accommodate the pencil lead 17. This bore is of sufficiently greater diameter to also accommodate a center tube 23. The center tube 23 is fixed in the end of the fitting 11 and as shown in Fig. 1 extends substantially the length of the pencil.

Fitted over the tube 23 is a tubular eraser 24. The outside diameter of this eraser is such as to fit snugly within the outer tubular body member 10, and this central bore 25 is such as to fit over the central tubular member 23. It is to be understood, however, that the eraser 24 is intended to slide longitudinally so that a working end of it may project beyond the end of the pencil for use.

Formed at the opposite end of the tubular body member 10 from that carrying the fitting 11 is a threaded portion 26 which receives a ferrule 27. This ferrule has a cylindrical portion 28 formed with a threaded bore to engage the threaded portion 26 and an inwardly tapered portion 29 which engages tapered faces 30 of yieldable clamping jaws 31. The jaws 31 are here shown as being formed as extensions of the tubular body member 10. These jaws are arcuate in cross-section and conform to the outer circumference of the eraser 24, thus, when the ferrule 27 is tightened down against the jaws 31, the eraser will be gripped and will be held against the longitudinal movement.

By reference to Fig. 5 of the drawing, it will be seen that the ferrule 27 engages the end of the body portion 10, by friction only, thus eliminating the threaded connection between the ferrule and the body portion. It will also be seen in Fig. 5 that the central tubular member 23 has been eliminated and that the pencil lead extends directly through the bore 25 of the eraser 24.

In operation of the present invention the pencil is assembled either as shown in Fig. 1 or in Fig. 5. When it is desired to adjust and set the lead 17 the tip portion 19 may be advanced by rotating it with relation to the threaded extension 14 of the fitting 11. This will relieve binding pressure against the yieldable jaws 16 and allow the pencil lead 17 to move longitudinally. When the pencil lead has been moved to

a desired position the tip member 19 may be tightened on the fitting 11 so that the jaws 15 grip the lead and hold it against longitudinal movement. When it is desired to adjust the eraser 24, the ferrule 27 may be advanced to relieve pressure upon the jaws 31. This will allow the eraser to be moved longitudinally to a desired position after which the ferrule 27 may be forced to set the jaws 31 and hold the eraser.

Attention is directed to the fact that the central tubular member 23 does not perform any feeding action of the eraser but serves as a backing so that when the jaws 31 are clamped against the eraser, the eraser will not collapse, but will be held between the jaws and the tubular member 23.

It will thus be seen that the structure here disclosed provides a simple and inexpensive pencil within which long refillable leads may be carried as well as an unusually long length of eraser within the same pencil structure, without producing a pencil which is objectionably long and cumbersome.

While I have shown the preferred form of my invention, it is to be understood that various changes may be made in the combination construction and arrangement of parts, by those skilled in the art, without departing from the spirit of the invention as claimed.

Having thus described my invention, what I claim and desire to secure by Letters Patent is:

1. A pencil structure comprising a tubular body member of usual pencil length, lead receiving and gripping means at one end thereof, a plurality of longitudinally extending jaws at the opposite end thereof, a tubular eraser mounted within the tubular body member and snugly fitting within the same, the center bore of said eraser being designed to accommodate pencil lead, and a ferrule longitudinally movable upon said jaws to hold the eraser in position.

2. A pencil structure comprising a rigid tubular body member fitted with lead gripping means at one end thereof and with a plurality of gripping jaws at the other end thereof, said jaws being of arcuate section and being circumferentially spaced, the outer faces of said jaws being longitudinally tapered, a tubular eraser slidably fitting within the tubular body member and having a central opening to accommodate a pencil lead, and a sleeve sliding over the tapered faces of the gripping jaws to frictionally engage a pencil lead around the circumference thereof and hold it against longitudinal movement.

3. A pencil structure comprising a rigid tubular body member fitted with a pencil lead holding means at one end thereof, a plurality of longitudinally extending yieldable jaws of arcuate section at the opposite end thereof, the inner faces of said jaws agreeing with the inner diameter of the tubular body member, a tubular substantially non-deformable eraser fitting within the tubular body member and extending beyond the ends of the jaws, the central bore of said eraser being designed to accommodate a longitudinally extending pencil lead, and a sleeve telescoping over and cooperating with the yieldable jaws to temporarily hold the eraser against longitudinal movement.
